UNITED STATES PATENT OFFICE.

FRANK WAYLAND, OF SALEM, MASSACHUSETTS.

LEATHER-WORKING MACHINE.

1,090,895.

Specification of Letters Patent. Patented Mar. 24, 1914.

Application filed July 8, 1911. Serial No. 637,397.

To all whom it may concern:

Be it known that I, FRANK WAYLAND, a citizen of the United States, and resident of Salem, in the county of Essex and State of Massachusetts, have invented new and useful Improvements in Leather-Working Machines, of which the following is a specification.

This invention relates to leather working machines for putting out, staking and ironing skins and leather, and consists chiefly in certain improvements upon and modifications of the leather working machine described in Letters Patent of the United States No. 975,628, dated Nov. 15, 1910.

In the accompanying drawings which illustrate one embodiment of the invention, Figure 1 is a perspective view of a machine containing the invention; Fig. 2 is an end elevation of the machine viewed from the left of Fig. 1; Fig. 3 is an enlarged detail view showing the arrangement of the rolls; and Fig. 4 is a detail of a yielding driving connection hereinafter to be described.

Referring to the drawings, A represents a frame, which is preferably of cast metal, for carrying the working parts of the machine. Extending from end to end of the frame are four rolls, two of which may be designated as the work rolls and two as the feed rolls. The two work rolls are shown at B and D, and the feed rolls at E and F. The work roll B is provided with a number of right and left handed helical grooves or channels b, meeting near the middle of the roll. In the bottom of each channel b is a cushion b' formed of a strip of rubber, felt, or other suitable resilient material protected by a resilient covering b" in the form of a strip of metal such as steel or brass (Fig. 3). The work roll D is provided with right and left handed helical blades d, corresponding with the helical grooves b and working therein.

The roll D is mounted on and journaled at its ends in the frame A. The roll E is also mounted on the frame A, and its ends are journaled in blocks a which slide in slots a', and are pressed downward by springs a". The work roll B and feed roll F are mounted on and journaled in swinging arms C which are pivoted to the ends of frame A at c.

When in operative position the relation between the rolls is as best shown in Fig. 3 that is, the sides of the blades d of roll D and the sides of their respective channels b press toward each other with the skin K therebetween, and the protected cushions b' in the bottoms of said channels also press toward the ends or edges of said blades with the skin K therebetween. The roll E presses the skin against the smooth surfaces of the roll B between the grooves; and the rolls E and F press one toward the other to pinch the skin K and act thereon as feed rolls to draw the skin upward out of the machine. On the shaft carrying rolls B and D respectively are the driving gears g and g'. These gears are connected by intermediate gears g² and g³, the gear g² being journaled on arm C and meshing with gear g, and the gear g³ being journaled at the pivot of two links l and l', the former holding gear g³ in mesh with gear g², and the latter holding gears g⁴ and g⁵ in mesh. It will be seen that in all positions of arm C and roll B, the four gears g, g², g³ and g' will remain in train, and will cause the rolls B and D to rotate in opposite directions as indicated by arrows in Fig. 3 whether said rolls are pressed together or not.

As already stated, when the rolls are in normal and operative position as shown in Fig. 3, the bladed roll D and the grooved roll B are so adjusted that the blades d press toward the sides of the grooves b on the lower side, or forward side, considered in relation to the direction of rotation of the rollers. When the arms C are thrown backward to separate the rolls F and B respectively from the rolls E and D as shown in dotted lines in Fig. 2, the straightening out of the links l and l' and the changed relative positions of the four gears will cause the blades d to move upwardly a short distance in the direction of the dotted line arrow in Fig. 3 to the position shown in dotted lines at d' in Fig. 3, thus retracting the blades d from the sides of the channels with which they coöperate. Similarly, when the roll B is forced closer against the roll D, the relative movement of the gears will tend to make the blades d move in the opposite direction and therefore press more tightly toward

the sides of the channels. Two objects are achieved by this action. First, it is possible by pressing the arms C, and consequently the rolls B, toward the roll D, to 5 vary the pressure upon the skin which is being acted upon by the rolls; and second, the blades d and the grooves b will automatically come into coöperative relation without any tendency to strike the outer 10 surface of the roll B or to have a shearing effect on the skin as the blades enter the grooves.

In order to be able to vary the pressure between the sides of the blades and the sides 15 of the grooves for varying conditions of work and varying kinds of qualities of skins, a lever m is pivoted to each end of the frame A and adapted when the operator presses down the rod n to swing the lower 20 ends of the arms C to the right as viewed in Figs. 1 and 2, thereby pressing the blades d more tightly toward the sides of the channels b. Thus, the force exerted by the working rolls upon the material being treated 25 may be varied at the will of the operator.

At one end of the grooved roll B is a pulley p which, by any suitable form of belting, drives the roll B and also the roll D through the above described train of gears. The roll 30 F is an idler roll. The roll E is provided with a pulley or sprocket wheel q which is connected by a belt or chain r with a sprocket or pulley s mounted on a suitable driving shaft. The roll E is covered with a 35 layer of felt e or other suitable cushioning material. The arms C and the rolls carried thereby may be swung away from the rolls E and D by any suitable mechanism such for example as that commonly used in fleshing 40 machines for separating rollers. It will therefore not be necessary to describe in particular the mechanism for swinging the arms C away from the rolls D and E.

In order that a yielding pressure may be 45 maintained between the blades d and the sides of the grooves b and in order to allow for any inequalities or variations in thickness in the skins being treated, a yielding connection is provided between the driving 50 gear g' and the roll D which is shown in detail in Fig. 4. This device consists of a disk H which is screwed to the gear g' and is provided with a recess in one side h, said disk and gear g' are loose on shaft d' of the roll D. Keyed fast to shaft d' are the oppositely extending levers d² lodged within 55 the recess h. Springs s press against the levers d² and the walls of the recess h being held in place by bolts h'; and similar bolts 60 h² extending through the opposite walls of the recess h limit the play of the levers d² in that direction. The springs s normally press the blades d yielding toward the sides of the grooves b. If required by any

variation in thickness of the skin a slight 65 relative movement is permitted between the blades d and the grooves b by the yielding of the springs s notwithstanding the continued and constant rotation of the gear g'. Thus the pressure or pinch exerted on the 70 skin between the sides of the blades and the sides of the grooves is automatically and yieldingly maintained; and this automatic yielding pressure between the sides of the blades and the sides of the grooves takes 75 place at all positions of the blades when in operative position within the grooves.

The roll B is preferably made hollow and is provided with an inlet pipe at one end and an outlet pipe at the other end for 80 the admision and discharge of steam from any suitable source of supply. Thus the roll B may be heated which is essential when the machine is being used for an ironing machine and is sometimes desirable when it 85 is used for a staking machine. Such a steam pipe is illustrated at t.

The operation of the machine is as follows: The rolls are opened by throwing the arm C to the dotted line position of 90 Fig. 2. It will be understood that the rolls are rotating in the directions indicated by the arrows. The skin is then thrown between the rolls and the rolls closed together to the operative position with the skin held 95 between them in the position shown at K in Fig. 3. The feed rolls E and F are pinched together sufficiently tightly to draw the skin upward and outward. The lower part of the skin is acted upon by the helically bladed and grooved rolls B and D. These work rolls stretch the skin lengthwise and also sidewise. The cushions b' 100 in the grooves b yield in response to variations in thickness of the skin as do the 105 blades d and the sides of the groove b. When one half of the skin has been sufficiently acted upon by the work rolls, the rolls are again thrown open and the skin turned about and the other half subjected 110 to the same treatment. It will be observed that as the feed roll E presses against the smooth surface between the grooves of the roll B, the skin is ironed as it is pulled upward by the feed rolls.

The helical grooves tend to straighten out and stretch the leather during the ironing process, and the edges of the grooves work into the grain of the leather and smooth out the roughness of the grain.

The blades d are preferably made sufficiently wide and thin, as clearly illustrated in Fig. 3, to be somewhat resilient, so as to yield slightly to irregularities in a skin passing between the blades and the coacting helical surfaces on roll B.

Thus it will be seen that this machine will perform the functions of putting out,

staking, and ironing, the first process being preferably done with a cold roll B, the staking being done with either a hot or cold roll and the ironing being done with a hot roll.

5 It will also be noted that the staking process is repeated during the ironing process and holds the skin out flat and extended while the ironing process is going on.

This machine possesses marked advantages over existing machines in that it wholly avoids wrinkling, tearing or marring of the skins and in that the putting out is done on both sides of the skins, whereas in other putting out machines the putting out 10 process is performed on one side of the skin; and this machine produces a better product than heretofore and a larger area in the manufactured leather for a given skin than has heretofore been possible to attain.

20 I claim:

1. In a leather working machine, a pair of rolls, one having helical blades, and the other having corresponding helical channels into which said blades project, and means automatically to cause the sides of said blades and the sides of said channels yieldingly to press one toward the other.

2. In a leather working machine, a pair of rolls, one having helical blades, and the other having corresponding helical channels into which said blades project, and means automatically to cause the sides of said blades and the sides of said channels yieldingly to press one toward the other irrespec- 30 tive of the position of the blades within the grooves.

3. In a leather working machine, a pair of rolls, one having helical blades, and the other having corresponding helical channels 40 into which said blades project, and cushions in the bottom of said channels protected by a flexible covering of metal.

4. In a leather working machine, a pair of rolls, one having helical blades and the other having corresponding helical channels 45 into which said blades project, and a pair of feed rolls, one of said feed rolls pressing toward the smooth surface of said channeled roll and constituting there with an ironing mechanism.

5. In a leather working machine, a pair of work rolls having coöperating helices, the helices of one roll overlapping the helices of the other roll when the rolls are in work- 55 ing position, one of said rolls being mounted on the machine frame, a movable support carrying the other roll adapted to move the latter roll bodily out of working position and wholly away from the other roll to provide a clear open space between said rolls and their helices for the insertion of a skin therebetween, and mechanism to operate 60 said movable support to open and close said work rolls, said work rolls being connected

by a train of gears adapted to cause said rolls to rotate in opposite directions and to remain in train in all positions of said working rolls.

6. In a leather working machine, a pair of work rolls having coöperating helices, the helices of one roll overlapping the helices of the other roll when the rolls are in working position, means to press the sides of the helices of one of said rolls toward the opposed sides of the helices of the other of said rolls, and means to vary such side pressure between said helices.

7. In a leather working machine, a pair of work rolls having coöperating helices, the helices of one roll overlapping the helices of the other roll when the rolls are in working position, one of said rolls being movable bodily out of working position and wholly away from the other roll to provide a clear open space between said rolls for the insertion of a skin, and means automatically to cause said helices to come into operative position when the rolls are again brought together.

8. In a leather working machine, a smooth surface ironing roll having right and left handed helical grooves, means to heat said ironing roll and a pressure roll pressing toward said ironing roll.

9. In a leather working machine, a pair of rolls, one having helical blades, and the other having corresponding helical channels into which said blades project, gears in train adapted to cause said rolls to rotate in opposite directions, the gear on one of said rolls being loose on its shaft and provided with a fitting having a recess therein adjacent to the shaft, an arm fast to the shaft and movable within said recess to permit limited relative rotation between said gear and shaft, and a spring coöperating with said arm and said fitting to urge said helical blades toward the sides of said channels.

10. In a leather working machine, a pair of rolls, one having helical blades and the other having corresponding helical channels into which said blades project, said rolls being movable away from and toward each other, a train of gears connecting said rolls to cause the rolls to rotate in opposite directions and to remain in mesh in all positions of said rolls, said gears being adapted during the movement of said rolls away from each other to cause said blades to swing away from the channel side normally engaged thereby, and during the movement of said rolls toward each other to cause said blades to swing toward the channel side normally engaged thereby.

11. In a leather working machine, a pair of rolls having thereon coacting helices, between which the skin passes, and means automatically to cause the opposed sides of

said helices yieldingly to press one toward the other.

12. In a leather working machine, a pair of rolls having thereon coacting helices between which the skin passes, the sides of the helices of one roll arranged to press side-
wise toward the sides of the blades of the other roll, one at least of said helices being

resilient and adapted to yield with relation to the other. 10

Signed by me at Boston, Massachusetts,
this sixth day of July 1911.

FRANK WAYLAND.
